CLAIM

I claim the ornamental design for a treadmill, as shown and described.

DESCRIPTION

FIG. 1 is a top perspective view of a treadmill design showing my new design.

FIG. 2 is a bottom perspective view of a treadmill.

FIG. 3 is a front view of a treadmill.

FIG. 4 is a rear view of a treadmill.

FIG. 5 is a left side view of a treadmill.

FIG. 6 is a right side view of a treadmill.

FIG. 7 is a top view of a treadmill.

FIG. 8 is a bottom view of a treadmill.

FIG. 9 is an enlarged view of the portion labeled FIG. 9 in FIG. 1; and,

FIG. 10 is an enlarged view of the portion labeled FIG. 10 in FIG. 2.

The broken lines indicating an enlargement portion of the design form no part of the claimed design.

1 Claim, 10 Drawing Sheets
